Patented Nov. 16, 1915.

UNITED STATES PATENT OFFICE.

JAMES W. BARWICK, OF THOMASVILLE, GEORGIA.

HOE.

1,160,238.

Specification of Letters Patent. Patented Nov. 16, 1915.

Application filed February 3, 1912. Serial No. 675,197.

To all whom it may concern:

Be it known that I, JAMES W. BARWICK, a citizen of the United States, residing at Thomasville, in the county of Thomas and State of Georgia, have invented certain new and useful Improvements in Hoes; and I do declare the following to be a full, clear and exact description of the invention, such as will enable others skilled in the art to 5 which it appertains to make and use the same, reference being had to the accompanying drawings, and to the letters and figures of reference marked thereon, which form a part of this specification.

10 My invention relates to hoes; and it has for its object to provide features of construction which make it possible to form the blade of lighter or thinner metal in cross section than heretofore and at the same time enable it to be made of greater length or width and if desired of less depth than in the past while affording the maximum of strength at points adjacent to the junction of the blade and eye and adjacent thereto, 20 and at the same time bringing the application of the eye and operating handle in such relation to the blade that the power in operation of the hoe is at such point as to render the hoe easier of manipulation and 25 with less fatigue and with more effectiveness than heretofore.

30 To the accomplishment of the foregoing and such other objects as may hereinafter appear the invention consists in the features hereinafter described and then sought to be particularly defined by the claim, reference being had to the accompanying drawing forming a part hereof, and in which:—

40 Figure 1 is a perspective of the whole implement; Fig. 2, a perspective of the hoe-blade; Fig. 3 a rear elevation of the hoe, without the handle, and with a portion of the blade and bracing shoulders broken away; Fig. 4 a vertical cross section on the line 4—4 of Fig. 3; and Fig. 5 a detail sectional view on the line 5—5 of Fig. 3.

45 In the drawing the numeral 1 designates the eye of the hoe which has formed as a part thereof a brace-plate 2 which extends below and also to opposite sides of the eye and converges toward its opposite ends

55 along both its top and bottom edges as indicated clearly in Figs. 1 and 3 of the drawing and which portion is adapted to bear against the rear face of the blade as illustrated.

60 The portions of the top edge of the brace-plate at opposite sides of the eye are off-set as shown in Figs. 1, 3 and 4 of the drawing so as to provide relatively prolonged shoulders 3 which will bear down on the top edge of the blade at both sides of the eye and afford top bearings for the blade at such points and thus take strain from off the 65 rivets by which the blade is attached to the brace-plate and prevent movement due to looseness when the connection of the attaching rivets becomes loosened in constant use of the hoe. The eye is also provided with 70 a bracing bead or flange 4 conforming to the semi-circular conformation of the lower half of the eye and undercut or recessed as at 5 to receive the edge of that portion of the blade between the portions which lie 75 beneath the laterally extending shoulders 3. By this construction the blade is reinforced and braced along and parallel with its top edge at opposite sides of the eye as well as along the lower section of the eye, and at 80 the latter portion in a semi-circular or inverted arch-like form so that the maximum strength and rigidity are attained.

85 The blade 6 is formed of steel, relatively thin in cross-section, and has a semi-circular recess 7 formed centrally in its top edge to receive the lower half of the eye so that the longitudinal axis of the handle 8 will lie partially below the top edge of the blade, thus bringing the line of application of 90 power below the top edge of the blade and nearer the point of greatest resistance in manipulating the hoe. This also makes it possible to apply the bracing shoulder along the top edge of the blade and also along the 95 lower half of the eye as previously described. These features together with the brace-plate formed and applied as described makes it possible to make the blade of lighter material than otherwise and also of increased width or length and without sacrificing strength at the most essential points in the area of the blade.

10 The upper opposite corners of the blade

are cut at an oblique angle and then curved or bent rearwardly as illustrated clearly in Figs. 1 and 2 so as to afford cutting blades 9 at the opposite corners of the blade which 5 are useful in cultivating cotton plants by inverting the hoe and cutting or weeding out the young plants. The length of the blade and the locating of the cutting blades at opposite corners insure uniform spacing of the 10 plants as the length or width of the blade serves as a gage for insuring the proper spacing of the plants. This is of value because hoes of the ordinary width are considerably less than the proper spacing of 15 the plants and when employed by the careless or indifferent laborer such as ordinarily obtainable they are indifferent as to the spacing and this results not infrequently in going over the field more than once for the 20 proper spacing of the plants. By constructing the blade as described however it is made possible to obtain the desirable results in view.

The blade is attached to the brace-plate by 25 the application of rivets 10 at the three points indicated which is sufficient for the purpose especially in view of the brace shoulders and other features of construction specified.

30 I have illustrated and described with particularity the features found best in actual practice for the objects in view but it is obvious that departures may be made from such specific details without departing from the

essential features as indicated in the ap- 35 pended claim.

Having described my invention what I claim is:—

The within described hoe comprising a relatively thin blade formed with a centrally 40 disposed recess in its upper edge to receive the lower portion of the eye which receives the handle, and a brace-plate, handle-receiving eye and laterally extending shoulders formed integral with each other, said eye 45 projecting from the front of the brace-plate so that its lower portion will fit within the recess in the top edge of the blade and bear against its walls and the upper portion will lie above the top edge of the blade, and said 50 laterally extending shoulders intersecting the handle-eye above the lower portion of the eye and at such point resting upon the top edge of the blade to brace the connection between the blade and eye at said point, the 55 brace-plate extending laterally beyond the outer ends of said shoulders below the top edge of the blade and bracing the body of the blade to a substantial extent beyond the ends of the shoulders, substantially as de- 60 scribed.

In testimony whereof I affix my signature in presence of two witnesses.

JAMES W. BARWICK.
